DESIGN FOR A DISPLAY STAND

Carl D. Wilke, Beatrice, Nebr.

Application October 16, 1937, Serial No. 72,240

Term of patent 7 years

To all whom it may concern:

Be it known that I, Carl D. Wilke, a citizen of the United States, residing at Beatrice, in the county of Gage and State of Nebraska, have invented a new, original, and ornamental Design for a Display Stand, of which the following is a specification, reference being had to the accompanying drawing, forming part thereof.

I claim:

The ornamental design for a display stand, as shown.

CARL D. WILKE.
